UNITED STATES PATENT OFFICE.

JOSEPH RYBA, OF CHICAGO, ILLINOIS.

GARBAGE-RECEPTACLE.

1,315,863.

Specification of Letters Patent.

Patented Sept. 9, 1919.

Application filed February 26, 1919. Serial No. 279,329.

To all whom it may concern:

Be it known that I, JOSEPH RYBA, a citizen of the United States of America, residing at Chicago, in the county of Cook and State of Illinois, have invented certain new and useful Improvements in Garbage-Receptacles, of which the following is a specification.

The primary object of the invention is to provide a receptacle for garbage and refuse that is sanitary and while readily receiving anything for which it is intended, automatically closes for preventing the escape of any dust or dirt as well as obnoxious fumes or gases.

A further object of the invention is to provide a receptacle adapted for automatically closing upon depositing anything therein and formed of material preventing the device being injured by its contents so that the same possesses great durability as well as strength and utility.

With these general objects in view, the invention consists of a receptacle that is easy and inexpensive to manufacture and is of the form hereinafter described in connection with the accompanying drawings and in which like reference characters designate corresponding parts throughout the several views.

In the drawings,

Figure 1 is a vertical central sectional view through the invention in its closed position, parts being indicated by dotted lines in their open positions,

Fig. 2 is a top plan view thereof,

Fig. 3 is a front elevational view of the same,

Fig. 4 is a view partly in side elevation and partly in vertical section,

Figs. 5 and 6 are detail sectional views taken upon lines V—V and VI—VI respectively of Fig. 1,

Fig. 7 is a perspective view of the sealing plate and its counterweight with the plate broken away,

Fig. 8 is a sectional view of a modified form of the invention closed and

Fig. 9 is a view thereof in its open position.

My garbage receptacle comprises a metallic box or casing 10 preferably having a hinged bottom 11 normally maintained closed by a spring latch 12 at the rear end 55 of the casing. Handles 13 are provided

upon the opposite ends of the casing for convenience in transporting the device.

A receiving hopper 14 is mounted upon the top 15 of the casing 10 having inclined front and rear walls 16 and 17 respectively, 60 the said hopper communicating with the interior of the casing 10 through an opening 18 in said top 15 thereof. A cover or lid 19 is provided for the hopper 14 hinged as at 20 to the rear upper edge of the hopper and 65 adapted for swinging to open position as illustrated in Fig. 2 of the drawings for convenience in placing garbage or refuse within the hopper 14.

An inclined cleat 21 is transversely secured within the hopper 14 upon the rear wall 17 thereof while an oppositely positioned curved brace 22 is attached to the front wall 16 within the said hopper.

A rectangular sealing plate 23 is connected by hinges 24 with the lower edge of the brace 22 for swinging within the hopper 14 beneath the cleat 21. An elongated counterweight 25 is adjustably positioned upon a reduced extension or arm 26 of the plate 23 80 at a point beneath the brace 22, the said counterweight 25 being adapted for normally maintaining the plate 23 in its closed position engaging the lower edge of the cleat 21. A locking screw 27 carried by the 85 weight 25 is adapted to engage the extension 26 for locking the cleat in any desired position upon the extension 26.

The operation of the invention will be fully understood, it being seen that the lid 90 19 is opened for placing the garbage in the hopper 14 upon the plate 23 which automatically swings downwardly under the weight of the garbage as illustrated by dotted lines in Fig. 1 of the drawings permitting the 95 garbage to fall through the mouth or opening 18 of the casing 10 into the said casing. The counterweight 25 automatically closes the plate 23 against the cleat 21 maintaining a tight seal against the escape of any 100 fumes from the interior of the casing 10 although being ready for the reception of additional garbage. When it is desired to lock the plate 23 against swinging movement, the weight 25 is forcibly moved upon 105 the extension 26 for engaging the hinge 24 and the adjacent side of the brace 22 as illustrated in Fig. 4 of the drawings while the screw 27 is employed for locking the weight in position, the operation of the hinge 110

24 being prevented by the engagement of the weight 25 with the brace 22. A slide door 28 is provided in the front wall 16 of the hopper 14 for convenience in adjusting 5 the weight 25 as well as for obtaining access to the interior of the hopper beneath the brace 22 whenever desired. The inner face 29 of the weight 25 is preferably rounded for permitting greater freedom of movement of 10 the plate 23 when the weight is retracted as illustrated in Fig. 1 of the drawings.

In the modified form of the invention shown in Figs. 8 and 9 of the drawings, the receptacle or casing 30 has an entrance hop- 15 per or neck 31 upon the top 32 thereof while a hinged lid 33 at the upper open end of the neck is pivotally connected by means of a link 34 with a plate 35 swingingly mounted in the neck. This arrangement is designed 20 for maintaining the plate 35 closed against a projection 36 in the neck 31 when the lid 33 is open as shown in Fig. 9 of the drawings. Garbage may then be placed upon the plate 35 which will automatically swing down- 25 wardly permitting the garbage to fall into the casing 30 and also closing the lid 33 upon the neck by means of the link 34.

A sanitary garbage receptacle is provided that remains normally closed, sealed against 30 the escape of fumes and gases although the hopper may at all times receive garbage by opening the lid 19, the plate 23 automatically opening and closing for the accommodation of the garbage.

35 What I claim as new is:—

1. A garbage receptacle comprising a casing, an entrance hopper upon the casing having oblique front and rear walls, an inclined cleat and a downwardly curved brace within

the hopper upon said rear and front walls 40 respectively, a sealing plate hinged to the lower edge of said brace adapted for downward swinging movement under the weight of garbage deposited in the hopper upon said plate, the said plate being normally positioned closed against the lower edge of said cleat, an extension upon the hinged edge of said plate beneath said brace, an elongated counterweight slidable upon said extension, a locking screw carried by said weight and a 45 sliding door in the front wall of the hopper opening at a point adjacent said weight beneath the brace. 50

2. A garbage receptacle comprising a cas- 55 ing, an entrance hopper upon the casing hav- ing oblique front and rear walls, an inclined cleat and a downwardly curved brace within the hopper upon said rear and front walls respectively, a sealing plate hinged to the lower edge of said brace adapted for down- 60 ward swinging movement under the weight of garbage deposited in the hopper upon said plate, the said plate being normally positioned closed against the lower edge of said cleat, an extension upon the hinged edge of 65 said plate beneath said brace, an elongated counterweight slidable upon said extension, a locking screw carried by said weight, a sliding door in the front wall of the hopper opening at a point adjacent said weight be- 70 neath the brace, the said cleat having a curved inner side providing clearance adjacent said brace, a closure lid upon the hop- 75 per, handles carried by the casing and a hinged bottom provided for the casing.

In testimony whereof I affix my signature.

JOSEPH RYBA.
